Primary Examiner — Richard E Chilcot

(57)

CLAIM

The ornamental design for a hair-cutting machine blade, as shown and described.

DESCRIPTION

1. Hair-cutting machine blade

1.1 : Front

1.2 : Back

1.3 : Bottom

1.4 : Top

1.5 : Right

1.6 : Left

1.7 : Perspective

The broken lines in the drawings depict environmental structure that forms no part of the claimed design.
